UNITED STATES PATENT OFFICE.

ERNEST FLAGG, OF NEW YORK, N. Y.

HINGE.

Application filed December 30, 1925. Serial No. 78,400.

This invention relates to a hinge.

An object of the invention is to provide a simple and efficient hinge as an improvement on the type of hinge shown in my 5 United States Patent No. 1,479,705, entitled Hinge construction and issued January 21st, 1924.

A further object is to provide a hinge, the engaging members of which will move relatively on ball bearings.

A further object is to provide a hinge construction which, when formed, will be more securely imbedded in the material of the door and the jamb.

15 A further object is to provide a ball bearing hinge construction in which the parts are of simple design to reduce the expense of manufacture, few in number and capable of being very readily assembled and disassembled.

The invention is illustrated in the drawings, of which—

Figure 1 is a horizontal section taken through a door and a jamb showing the hinge 25 members in place;

Figure 2 is a vertical section taken on the line 2—2 of Figure 1;

Figure 3 is a vertical section taken on the line 3—3 of Figure 1;

30 Figure 4 is a side elevation of the hinge;

Figure 5 is a plan view of one of the hinge members in blank form;

Figure 6 is a similar view of the other hinge member in blank form.

35 The form of the invention shown in the drawings is a preferred form, although it is understood that modifications in the construction and arrangement of the parts and in the character of the materials used may 40 be adopted without departing from the spirit of the invention as set forth in the appended claims.

In its general aspect this invention relates to a hinge in which the hinge plates preferably project into the material of the door and the jamb, at right angles to the surface thereof, so as to directly aid in bearing the load of the door rather than putting this weight on a few screws.

50 It is further contemplated to provide the hinge plates on their end portions projecting from the door and the jamb surfaces with ball bearing race casings held together and related in a simple manner so as to reduce the friction in the operation of the hinge members to a minimum.

In the preferred form of the invention shown in the drawings the hinge members are formed as blanks having portions 10 and 11 in the form of flat plates pointed as at 12 and 13 to project into a suitable slot or saw cut formed respectively in the jamb and the door 14 and 15. Adjacent these plates are disposed strips 16 and 17 which are bent up to form tubular members, from the forward portion of each of which toothed prongs such as 18 and 19 project. These are adapted to be driven into the wood of the door and jamb and to lock therewith in order to hold the hinge elements in place. These tubular members are adapted to fit into bores such as 20 and 21 formed in the door and jamb adjacent one edge of the saw cuts above mentioned. The hinge elements are also provided with rearwardly extending plates such as 22 and 23, one of which, 23, is adapted to have its periphery bent up, as shown in Figure 2, to form a flanged, cup-like receptacle to receive ball bearings 24. The other plate 22 is adapted to have its central portion flanged downward to form a flange such as 25, (see Figure 2) thus providing between the turned up flange on the plate 23 and the downturned flange on the plate 22, a channel for the reception of the ball bearings. A cover plate 26 is disposed over the two hinge plates and is provided with an aperture alined with an aperture 27 formed in the plate 23 and these apertures receive a headed locking pin 28 which is provided with a head 29 and split prongs 30 and this holds the various plates firmly together.

The rear edges of the strips 16 and 17 are provided with a plurality of spaced ears 31, which when the strips are bent up in tubular form are turned inwardly, as shown in Figures 1 and 2 to partially close the end of the tube and to give it a finished appearance, and also to form a surface which can be lightly struck by a hammer or other light tool to drive the hinge elements into place.

In the operation of assembling the hinge and mounting it on a door and a jamb it is to be understood that the strip portions 16 and 17 are rolled up and the extension plate portions 22 and 23 are bent to the proper form as described. The hinge plate 10 is then inserted in the saw cut in the door 15 with the tube 16 projecting into the bore 20 and the prong 18 projecting into the wood of the door. Likewise the hinge element 11 is inserted into the saw cut in the jamb 14

with the tube 17 rolled up and disposed in the bore 21 with the prongs 19 projecting into the wood of the jamb. With the plate 22 overlying the plate 23 and the balls 24 in position, the cover plate 26 is disposed thereover and the locking pin 28 is put into place to hold the device together.

This hinge construction is therefore extremely simple and efficient and durable.

10. What I claim is:

1. A device for fastening hinge members and the like to a support which includes a plate portion, a tubular member on the plate portion, said tubular member and a portion 15 of the plate adapted to be inserted respectively into a tubular bore and a slot in the support, the outer end of the tubular portion being closed to offer a surface to be struck by a hammer when forcing the device into embedded position within the support.

2. A device for fastening hinge members and the like to a support which includes a plate portion, a tubular member on the plate portion, said tubular member and a portion 25 of the plate adapted to be inserted respec-

tively into a tubular bore and a slot in the support, the outer end of the tubular portion being closed to offer a surface to be struck by a hammer when forcing the device into embedded position within the support, 30 the closed end of the tube being formed by a plurality of spaced inwardly turned tongues integral with the end of the tubular member.

3. A hinge construction which comprises 35 a pair of hinge plates, a portion of one plate being bent up at its edges to form a cup, and centrally raised to form a boss, a portion of the other plate having a relatively large central opening therein, the material 40 at the edges of the opening being bent down to form a flange encircling the boss, said flange defining with the flange of the cup, a ball race, a cover plate to be disposed over said plate portions, centrally depressed to fit 45 within the opening in the upper plate, said cover plate and boss having aligned apertures therein for the reception of an interlocking pin for holding the plates together.

ERNEST FLAGG.
